METHOD OF CONDITIONING INK FORM ROLLS William F. Smith, Jr., 504 S. Lake Shore Drive,
Mundelein, Ill.No Drawing. Filed Nov. 13, 1962, Ser. No. 237,356
2 Claims. (Cl. 101—426)

This invention relates generally to innovations and improvements in the art of printing and to novel compositions for bringing about such improvements. More specifically, this invention applies to methods of printing where ink or coating material is applied to a printing plate by means of an ink carrying roll. As used herein, the term printing refers not only to wording, figures and pictures, but also to background designs and solid printed or coated areas. The printing may be black or in various colors, including multi-color printing.

It is common in printing to transfer ink from a fountain or reservoir through a series of rubber, metal, and/or plastic rolls to the surface of the printing plate. Various known types of printing plates are attached to the plate cylinder such as metal, rubber, plastic or paper. From the printing plate the ink or coating material is either directly applied to the surface to be printed or applied to an intermediate cylinder which in turn applies the ink or coating material to the surface to be printed. The last in the series of rolls that bring the ink to the printing plate are normally called form rolls. These form rolls actually contact the surface of the printing plate. These ink form rolls are used in conventional presses whether the type of printing be typographic (e.g. letter press) or planographic (e.g. offset or lithographic).

One problem that has plagued operators of printing presses has been that of foreign matter sticking to the surface of the printing plate so as to prevent ink from being applied to the printed sheet in that area. Such foreign matter is commonly referred to by the press operators as "hickies."

These "hickies" necessitate:

- (a) Shutting the press down and cleaning the foreign matter from the surface of the plate.
- (b) Continuing to run the press and sorting and discarding bad sheets away when the job is completed.

(c) Operators risking permanent physical injury by attempting to remove the foreign matter from the printing plate with their fingernails while the press is in operation.

I have discovered, in accordance with my present invention that if a tacky material having the tacky properties of, or closely similar to those of, urethane rubber prepolymer or monomer is applied to the surface of at least one roll in the roller chain, preferably one of the so-called ink form rolls, that the formation of hickies on the printing plate can be greatly minimized, and usually entirely prevented. After a period of running, e.g. five to eight hours, it will usually be necessary to clean off the ink rolls and re-apply the tacky material thereto. However, as long as the tacky deposit is maintained, hickies can be avoided.

Accordingly, the object of the invention, generally stated, is a method of, and compositions for, eliminating poor quality printed sheets due to foreign matter or hickies that stick to a printing plate or surface.

A more specific object is the improvement in printing which comprises maintaining on at least one ink roll a deposit of a tacky substance having the tackiness properties of, or closely similar to those of, urethane rubber prepolymer and cleaning the rolls and re-applying the tacky substance as required.

Another important object of the invention is the provision of compositions for imparting such a tacky de-

2

posit on the surface of a printing press ink form roll comprising urethane rubber prepolymer dissolved in a volatile carrier such as methylene chloride.

A further object of the invention is a pressure package, or aerosol package, containing a volatile propellant and a composition for imparting a tacky deposit on the surfaces of printing press form rolls comprising urethane rubber prepolymer dissolved in methylene chloride.

Certain other objects of the invention will, in part, be obvious and will in part appear hereinafter.

I have discovered that a preferred material for giving the correct tackiness to the ink form rolls of the printing press is urethane rubber prepolymer or monomer. This is a known material that is available from several commercial sources such as Thiokol Chemical Corp. (Solithane 113 and 291), and E. I. du Pont de Nemours and Co. (Adiprene L100, L167, L315). Such materials are liquids and have isocyanate contents ranging from about 3% to about 4.3% by weight.

While the urethane rubber prepolymer is the substance of choice, other materials that will afford similar tacky surfaces may be used such as the chlorinated biphenols such as commercially available from Monsanto Chemical Co., under the trade name of Aroclor, or the polybutenes manufactured by the Oronite Co., or other slow drying tacky substances of a similar nature.

The urethane prepolymers and these other substances may be classified as tacky, non-drying substances that may be solvanted in a volatile solvent such as methylene chloride.

The composition may be applied to the ink form rolls of a printing press in several ways such as by wiping on, brushing on, spraying on, or dipping the rolls in the solution. Spraying on from a pressure package of aerosol can or container constitutes a preferred technique of application in that a uniform thin deposit of the urethane or other tacky substance may readily be obtained without removing the ink form rolls from the press.

A preferred composition for either method of application is 1 part by weight of urethane rubber prepolymer dissolved in 10 parts by weight of methylene chloride. Other volatile solvents that may be used include methyl ethyl ketone, toluol, acetone or butylacetate.

It appears that the tacky deposit of urethane rubber has just the appropriate tackiness to keep the printing plate clean and free of hickie forming foreign substances without interfering with the normal operation of the printing plate. After some time in operation, e.g. five to eight hours, it will be advisable to stop the press and to clean the ink form rolls so as to remove the tacky deposit therefrom which by this time will begin to lose its efficiency. A new deposit may be readily formed and the operation of the press resumed. Any suitable solvent may be used for removing or cleaning the ink form rolls such as the methylene chloride solvent itself. Thus, the frequency of shut down for preventing hickies (not to mention the safety factor) is greatly reduced and the saving in time and labor and increase in production are such as to exceed by many times the cost of the compositions.

What I claim as new is:

1. In printing the improvement which comprises applying to the surface of at least one ink form roll of the press, liquid urethane rubber prepolymer having an isocyanate content in the range of from about 3% to about 4.3% by weight, and periodically cleaning said form roll and applying an additional amount of said urethane rubber prepolymer.

2. The improvement of claim 1 wherein said urethane rubber prepolymer is applied as an aerosol spray.
